US00D752938S

(12) **United States Design Patent**
West et al.

(10) **Patent No.:** US D752,938 S
(45) **Date of Patent:** ** Apr. 5, 2016

(54) **HAMMER**

(71) Applicant: **Estwing Manufacturing Company, Inc.**, Rockford, IL (US)

(72) Inventors: **Joshua D. West**, Rockford, IL (US); **John W. Ryan, Jr.**, Belvidere, IL (US); **Robert H. Youngren**, Stillman Valley, IL (US)

(73) Assignee: **ESTWING MANUFACTURING COMPANY, INC.**, Rockford, IL (US)

(**) Term: **14 Years**

(21) Appl. No.: **29/485,019**

(22) Filed: **Mar. 14, 2014**

(51) LOC (10) Cl. **08-02**

(52) U.S. Cl.

USPC **D8/78**

(58) **Field of Classification Search**

(57) **CLAIM**

The ornamental design for a hammer, as shown and described.

DESCRIPTION

FIG. 1 is an isometric view of a front, top, and left side of an ornamental design for a hammer;

FIG. 2 is a left side elevational view of the hammer of FIG. 1; FIG. 3 is a right side elevational view of the hammer of FIG. 1;

FIG. 4 is a rear elevational view of the hammer of FIG. 1; FIG. 5 is a front elevational view of the hammer of FIG. 1;

FIG. 6 is a top plan view of the hammer of FIG. 1; and, FIG. 7 is a bottom plan view of the hammer of FIG. 1.

The dash-dash-dash-dash lines are for the purpose of illustrating environmental structure and form no part of the claimed design. The dot-dash-dot-dash lines are for the purpose of illustrating the boundaries of the claimed design.

1 Claim, 5 Drawing Sheets
